Primary Examiner — Cynthia Ramirez*Assistant Examiner* — Llorellys Martinez-Rivera(74) *Attorney, Agent, or Firm* — Frost Brown Todd LLC(57) **CLAIM**

The ornamental design for a casing bead with removable leg, as shown and described.

DESCRIPTION

FIG. 1 is a top perspective view of a casing bead with removable leg, showing our new design;

FIG. 2 is a bottom perspective view thereof;

FIG. 3 is a left elevational view thereof;

FIG. 4 is a right elevational view thereof;

FIG. 5 is a back elevational view thereof;

FIG. 6 is a front elevational view thereof;

FIG. 7 is a top elevational view thereof; and,

FIG. 8 is a bottom elevational view thereof.

The casing bead with removable leg is shown with a symbolic break in its length. The appearance of any portion of the casing bead with removable leg between the break lines forms no part of the claimed design. The broken lines in FIGS. 1-2 and 4-8 illustrate environmental subject matter only and form no part of the claimed design.
